UNITED STATES PATENT OFFICE.

FRANK L. O. WADSWORTH, OF MORGANTOWN, WEST VIRGINIA, ASSIGNOR
TO PRESSED PRISM PLATE GLASS COMPANY, OF NEW YORK, N. Y., A
CORPORATION OF WEST VIRGINIA.

APPARATUS FOR GRINDING AND POLISHING.

No. 845,987.

Specification of Letters Patent.

Patented March 5, 1907.

Application filed June 24, 1905. Serial No. 266,696.

To all whom it may concern:

Be it known that I, FRANK L. O. WADSWORTH, of Morgantown, Monongalia county, West Virginia, have invented a new and useful Apparatus for Grinding and Polishing, of which the following is a full, clear, and exact description, reference being had to the accompanying drawings, forming part of this specification, in which—

10. Figure 1 is a bottom plan view of a grinding-shoe embodying my invention, and Fig. 2 is an elevation partly in section.

My invention relates to the class of grinding and polishing machines for plate-glass, 15 and is designed to increase the speed of the operation and at the same time improve the action of the grinding or polishing surfaces upon the glass.

It consists in a novel construction of the 20 grinding blocks or shoes.

One of the features of the invention lies in the peculiar construction of the grinding-shoes. As shown in Fig. 1, these shoes 2 consist, preferably, of sector or wedge shaped 25 castings, which may be secured by bolts 3, extending through five holes in each shoe. These shoes may be cast interchangeably, so that they can be removed and replaced without removing and turning over the grinding- 30 runners.

The lower face of the casting is provided with a series of grooves 4, the general direction of which is inclined both to the radius and circumference of the general circle of the disk. The grooves extend in a zigzag direction 35 continuously from one radial edge of the shoes to the opposite radial edge, their ends communicating with the radially-extending spaces between the edges of adjacent shoes.

40. The grooves are also preferably made in zigzag or sinuous form, as shown, so that the sand will travel through them at an uneven rate. It travels faster in those parts approaching circumferential lines and slower in the parts approaching the radial lines. This 45 retains the sand for short intervals of time in the radial portions of the grooves and makes the grinding action more rapid.

As the movement of the table is in the same direction as that of the disks and at a 50 higher speed, the motion of the table will force the sand through the grooves at one side of the segment and suck it through the grooves on the opposite side at any given moment. The movement of the sand 55 through the grooves is therefore made positive and the grinding action more rapid.

Many changes may be made in the form and arrangement of the various parts without departing from my invention.

I claim—

1. In a glass-grinding apparatus, a disk having shoes of sector or wedge shape form, radiating from the center of the disk and provided with grooves which extend continuously from one radial edge of the shoe to the opposite radial edge; substantially as described.

2. A grinding-disk having shoes formed with grooves therein, portions of said grooves 70 being approximately radial, and other portions thereof being approximately circumferential in direction; substantially as described.

3. A grinding-disk having shoes with zig- 75 zag or sinuous grooves extending continuously from one radial edge of the shoes to the other; substantially as described.

4. A grinding-disk having a series of sepa- 80 rated sector-shaped shoes formed with zig-zag grooves extending from one radial edge of the shoe to the opposite radial edge; sub- stantially as described.

5. A grinding-shoe having therein a plu- 85 rality of zigzag grooves, portions of which extend in substantially radial directions, and other portions of which extend in substan- tially circumferential directions; substan- tially as described.

In testimony whereof I have hereunto set 90 my hand.

FRANK L. O. WADSWORTH.
